SHOE

Robert James Burke, Bourbon, Ind., assignor to Mishawaka Rubber and Woolen Manufacturing
Company, Mishawaka, Ind., a corporation of Indiana

Application March 1, 1950, Serial No. 8,241

Term of patent 14 years

(Cl. D7—7)

To all whom it may concern:

Be it known that I, Robert James Burke, a citizen of the United States, residing at Bourbon, in the county of Marshall and State of Indiana, have invented a new, original, and ornamental Design for a Shoe, of which the following is a specification, reference being had to the accompanying drawing, forming part thereof.

Fig. 1 is a side view of a shoe showing my new design; and

Fig. 2 is a front view of the shoe shown in Fig. 1.

I claim:

The ornamental design for a shoe, as shown.
ROBERT JAMES BURKE.
